CLAIM

The ornamental design for a bandage, as shown and described.

DESCRIPTION

FIG. 1 is a front perspective view of a bandage of our design. FIG. 2 is a back perspective view of the bandage of FIG. 5.

FIG. 3 is a front view of the bandage of FIG. 5.

FIG. 4 is a back view of the bandage of FIG. 5.

FIG. 5 is a top view of the bandage of FIG. 5.

FIG. 6 is a bottom view of the bandage of FIG. 5.

FIG. 7 is a first side view of the bandage of FIG. 5; and, FIG. 8 is a second side view of the bandage of FIG. 5.

Randomly dashed lines represent surface shading.
